CLAIM

I claim the ornamental design for a faucet-mounted multi-flavored water dispensing unit, as shown and described.

DESCRIPTION

FIG. 1 is a perspective view of a faucet-mounted multi-flavored water dispensing unit, illustrated with a flavored concentrate compartment cover in an open position, showing my new design;

FIG. 2 is a front elevational view of the invention, illustrated with the flavored concentrate compartment cover in a closed position;

FIG. 3 is a rear elevational view of the invention, illustrated with the flavored concentrate compartment cover in the closed position;

FIG. 4 is a left-side elevational view of the invention, illustrated with the flavored concentrate compartment cover in a closed position;

FIG. 5 is a right-side elevational view of the invention, illustrated with the flavored concentrate compartment cover in a closed position;

FIG. 6 is a top plan view of the invention, illustrated with the flavored concentrate compartment cover in a closed position; and,

FIG. 7 is a bottom plan view of the invention, illustrated with the flavored concentrate compartment cover in a closed position.

The broken lines showing a sink faucet dispensing water into a cup in FIG. 1 are included for the purpose of illustrating the invention in use, and forms no part of the claimed design.
